UNITED STATES PATENT OFFICE.

EDGAR RAY HAWLEY, OF SALT LAKE CITY, UTAH.

AUTOMATIC TRAP.

1,149,915.

Specification of Letters Patent.

Patented Aug. 10, 1915.

Application filed November 5, 1914. Serial No. 870,504.

To all whom it may concern:

Be it known that I, EDGAR R. HAWLEY, a citizen of the United States, and a resident of Salt Lake City, in the county of 5 Salt Lake and State of Utah, have invented certain new and useful Improvements in Automatic Traps, of which the following is a specification.

My invention relates to steam systems, as 10 for heating and other purposes, and the main object is to provide means for automatically producing a vacuum in the pipes of such systems without the necessity for the pumps at present employed.

15 A further object is to provide means for producing this result by means of the water of condensation, as from radiators, coils, condensing units, etc.; and further objects are to provide such devices which are very 20 simple in construction, readily installed in new or existing systems, entirely automatic in operation, requiring no pumping mechanism, highly efficient, operative at the moment of need, composed of but few parts 25 not likely to get out of order to require repair, and very inexpensive.

My invention is fully described in the following specification, of which the accompanying drawings form a part, in which 30 the separate parts are designated by the same reference characters in each of the views, and in which:—

Figure 1 is a longitudinal, vertical, section taken through a trap constructed in accordance with my invention, with the parts 35 in the positions of one stage of the operation; and Fig. 2 is a similar view with the parts in another stage.

In the drawings forming a part of this 40 application I have illustrated one form of embodiment of my invention, comprising a tank 3 into which the return pipe 4 of a steam system deposits the water of condensation, a check-valve 5 being provided in said pipe, and said tank is provided with an air outlet and check-valve 6, not shown in detail as many types thereof are now in use, a steam inlet pipe 7, and a water outlet pipe 8 having a check-valve 9 therein, the check- 45 valve 5 preventing the flow of steam from the tank 3 backwardly through the pipe 4, and the check-valve 9 preventing the back- 50 ing up of fluids from the pipe 8 to the tank 3, and this check-valve is of such form as to

resist the weight of the water in the tank 55 3 at all times.

Arranged within the tank 3, at one end thereof, is an air compression chamber 11 having a U-shaped pipe 12 at the bottom thereof and which pipe is formed into a nozzle 13 at its outer end and which nozzle is directed inwardly of the tank 3, and at the other end of said tank is a float chamber 14 having a float 15 therein which carries a rod 16 thereover and to the upper end of which is connected a valve 17 normally closing a steam inlet port 18 between the steam pipe 7 and the tank 3, and I may also employ a supplemental float 19 to assist the float 15 to raise said valve 17 from its seat, 70 but the latter float 19 is not connected with the valve steam 16, merely bearing against the under side of a stop 20 thereon in the raising operation of the valve 17, and it will be noted that the float chamber 14 extends well toward the top of the tank 3, for 75 reasons later explained.

Imprisoned, by means of a casing 21, beneath the float chamber 14 is a float 22 which carries a valve 23 adapted to close a 80 port 24 in the bottom of said chamber 14 but normally out of such closer position, and the float 22 is preferably guided in its movement, as by means of a stem 25, the water in the tank 3 being at all times free to 85 pass around and under this float 22.

Assuming the parts to be in the positions shown in Fig. 2, with the tank empty, and the water of condensation from the steam system passing into said tank through the 90 return pipe 4, it being recalled that the check-valve 9 not being opened by the weight of the water in the tank at any time; the water in the tank rises and raises the float 22 until the valve 23 thereon shuts the port 95 24 in the chamber 14, this chamber being of course empty at this time; the air compression chamber 11 is free from water also at this time, but some water remains in the nozzle pipe 12 to form an air seal, and the 100 water in the tank 3 continues to rise until it reaches the top of the float chamber 14 and into which it begins to flow, thereby raising the float 15 and lifting the valve 17 from its seat. Live steam from the boiler is now 105 free to enter the tank 3 from the pipe 7 and, when the pressure therein is sufficiently great, approximately that of the pressure

within the boiler, the check-valve 9 is opened and the water in the tank 3 begins to escape. This steam pressure also forces water into the submerged nozzle pipe 12 and into the chamber 11, thus compressing the air therein, and this compression is held as long as the steam pressure obtains in the tank 3. As the water is thus forced from the tank, through the check-valve 9, the level thereof sinks until the float 22 falls and thereby opens the port 24 in the chamber 14, but the steam valve 17 has been maintained in open position in the meantime because of the inability of the water in the chamber 14 to escape, and, when said port 24 is thus opened, the water in the chamber 14 escapes, the valve 17 is closed and the steam is prevented from entering the tank 3. The tank is, at this time, still filled with the live steam but no longer under pressure from the boiler and, thus, not of sufficient pressure to resist the expansion of the air compressed within the chamber 11, this expansion forcing the water in said chamber 11 and in the pipe 12 thereoutof, preferably in a fine spray directed over a considerable area of the tank 3 and which immediately condenses the steam within the tank 3 and thereby causes a vacuum therein which is also caused in the return pipe 4 of the steam system, and live steam is thus drawn through the system, the tank 3 again fills, and the operation is repeated as long as the steam is on.

The supplemental float 19 may or may not be provided, as its use will depend upon the resistance of the steam within the pipe 7, and it will be noted that this float may fall with the water without any effect upon the valve 17, this valve only being lowered when the float chamber 14 is emptied upon the opening of the port in the bottom thereof; in the drawings I have indicated the normal positions of the check-valves 5 and 9 by the reference characters α and γ , respectively, although these positions would have been clearly understood by anyone skilled in the art to which my invention appertains, and, as stated, any suitable type of check-valve may be employed provided that they operate in the manner described.

While I have shown a present preferred combination of elements producing the desired result, I do not limit myself thereto, as many other forms thereof may be designed which will incorporate the principles involved and be as efficient as the form shown, or, possibly, more so, which will not

be a departure from the spirit of my invention, or which will not sacrifice its advantages.

Having fully described my invention, what I claim as new, and desire to secure by Letters Patent, is:—

1. In combination with the return pipe of a steam system, a steam-tight tank having a chamber therein of relatively small diameter, open at its top, a discharge pipe and a steam inlet pipe for said tank, a float in said chamber, a valve for said steam inlet carried by said float, means for condensing steam in said tank to produce a vacuum therein, and means for preventing the upward movement of said float and valve until the accumulated water of condensation in said tank overflows the top of said chamber.

2. In combination with the return pipe of a steam system, a steam-tight tank having a chamber therein of relatively small diameter, open at its top, a discharge pipe and a steam inlet pipe for said tank, a float in said chamber, a valve for said steam inlet carried by said float, means for condensing steam in said tank to produce a vacuum therein, and means for preventing upward movement of said float to actuate said valve until the water of condensation overflows the top of said chamber, said chamber having a port in the lower end thereof, and said means comprising a supplemental float and a valve thereon adapted to close said port to prevent the accumulating water of condensation from entering said chamber.

3. In combination with the return pipe of a steam system, a steam-tight tank having a chamber therein of relatively small diameter, open at its top, a discharge pipe and a steam inlet pipe for said tank, a float in said chamber, a valve for said steam inlet carried by said float, means for condensing steam in said tank to produce a vacuum therein, means for preventing the upward movement of said float and the valve until the accumulated water of condensation in said tank overflows the top of said chamber, and a supplemental float for insuring valve operation in the event of said first named float being rendered inoperative.

In testimony whereof I have signed my name to this specification in the presence of two subscribing witnesses.

EDGAR RAY HAWLEY.
